UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

FRICITION-CLOSURE.

1,162,694.

Specification of Letters Patent.

Patented Nov. 30, 1915.

Application filed April 4, 1914. Serial No. 829,468.

To all whom it may concern:

Be it known that I, JOHN M. HOTHERSALL, a citizen of the United States, residing in Brooklyn, in the county of Kings and State of New York, have invented a new and useful Improvement in Friction-Closures, of which the following is a specification.

This invention relates to a friction closure suitable for closing varnish cans and similar uses. And the invention consists in the combination with the cylindrical can neck of an inverted cup-shaped frictional gripping cap the flange of which is bent into outward projections at intervals which may be flattened to loosen the grip in removing the cap.

In the accompanying drawing, Figure 1 is an elevation of a varnish can; Fig. 2 a similar view of the friction grip closure; Fig. 3 a plan view of the varnish can; Fig. 4 a section on the line 4—4 of Fig. 2 of the can neck and its friction grip cap, the latter being shown applied to the former; Fig. 5 a bottom view of the friction grip cap; and Fig. 6 a section on the line 6—6 of Fig. 5 of the friction grip cap.

The object of the invention is to produce a sheet metal friction grip cap suitable to be applied to close for example the mouth of a varnish can, said cap being so contrived that it may be readily put on and pressed down to a tight closure, when it will grip the can mouth so closely that it cannot under ordinary conditions be removed, and further so contrived that by the application of lateral pressure flattening down outward projections the grip of the cap may be so loosened that it can thereafter be readily removed and slipped on and off.

In said drawing, A is an ordinary varnish can having a neck B terminating at its upper end with a stiffened cylindric collar C, D is the inverted cup-shaped cap having the vertical downwardly projecting flange d. At intervals in the circumference of the flange d the outward projections e are formed preferably extending upward from the lower edge of said flange to about one-half its width. These projections give a

certain amount of lateral resilience to the 50 cup-shaped cap, the flange of which should fit very closely about the cylindric collar of the can mouth. In the interior of the cap there is shown, in the example illustrated a packing ring f and a packing disk g, useful 55 to effect a liquid-tight closure. A notable fact connected with the use of such a cap as that herein shown, is that when the same is pressed down upon the collar of the can neck firmly it cannot, under ordinary conditions, be removed, an unexpected result, due 60 to the peculiar action of the projections combined with the flange containing them, in conjunction with the cylindric can neck collar. However, after the cap is once applied and thus firmly secured it may be easily loosened by simply flattening down 65 the projections in the cap flange which enlarges its circumference and loosens the frictional grip so that thereafter the cap can 70 easily be slipped on and off.

When the cap is first applied and while it is exerting its frictional grip it holds its place very firmly as may be illustrated by the circumstance that a varnish can 75 provided with such a cap was put under an internal pressure of 10 pounds per square inch above atmosphere without loosening the cap, although the pressure was so great as to bulge the can itself out of shape. This 80 closure is exceedingly cheap and possesses in itself the function of a closure which will permit the contents to be shipped safely and which may be readily changed to one which can be slipped on and off with the fingers 85 easily.

I claim:

In a cylindrical closure for containers, in combination: a neck formed with a stiffened cylindrical collar comprising a horizontal 90 outwardly extending flange terminating in a flange forming a vertical friction wall, said wall terminating in an inwardly extending flange abutting firmly against said neck; a packing disk and ring loosely applied to the mouth of said neck on said horizontal flange; and a sheet metal cap having a depending cylindrical flange provided

with outward projections at intervals of its circumference, which may be readily flattened, said cap being adapted to be forcibly applied over the mouth of said neck to force said packing ring against said packing disk to form a liquid tight closure of the container, the flange of said cap having then a

tight frictional engagement around said vertical friction wall of the neck.

JOHN M. HOTHERSALL.
